ABSTRACT OF THE DISCLOSURE

A process for the separation and recovery of unsaturated aliphatic hydrocarbons from admixture with saturated aliphatic hydrocarbons by means of selective complex formation using cuprous fluoroborate and cuprous fluorophosphate as the complexing agent.

BACKGROUND OF THE INVENTION

The present invention relates to a process for the separation, purification and recovery of certain hydrocarbons. More particularly, the present invention relates to a process for the separation and recovery of unsaturated aliphatic hydrocarbons from admixture with saturated aliphatic hydrocarbons.

A separations problem which has required and received considerable attention is that of separating unsaturated aliphatic hydrocarbons such as olefins from close boiling and difficultly separable saturated aliphatic hydrocarbons such as the paraffin and naphthene hydrocarbons. Many processes have been proposed for such separations including liquid-liquid extraction, extractive distillation, selective adsorption, easy tropic distillation, as well as complex formation. With respect to this latter technique as applied to the separation of unsaturated aliphatic hydrocarbons from saturated aliphatic hydrocarbons, various complexing agents have been described, including such salts as cuprous chloride. However, none of these have been found acceptable to present, primarily, as a result of poor selectivity and/or the inability to recover the olefin hydrocarbons from the resulting complexes.

It is an object of the present invention to provide a new and improved process for the separation of hydrocarbons. It is another object of the present invention to provide a new and improved process for the separation of unsaturated aliphatic hydrocarbons from saturated aliphatic hydrocarbons. Another object of the present invention is to provide a new and improved process for the separation of olefin hydrocarbons from paraffin and/or naphthene hydrocarbons. An additional object of the present invention is to provide a process for the separation of unsaturated aliphatic hydrocarbons from admixture with saturated aliphatic hydrocarbons by means of complex formation. Another object of the present invention is to provide a process for the separation of unsaturated aliphatic hydrocarbons from admixture with saturated aliphatic hydrocarbons by selectively complexing the unsaturated aliphatic hydrocarbons from said mixture and a means for recovering the complexed unsaturated aliphatic hydrocarbons from decomplex. Additional objects will become apparent from the following description of the invention herein disclosed.

SUMMARY OF THE INVENTION

The present invention, which fulfills these and other objects, is a process for the separation of unsaturated aliphatic hydrocarbons from admixture with saturated aliphatic hydrocarbons which comprises contacting such a mixture with a first complex which comprises a cuprous salt selected from the group consisting of cuprous fluoro-

2

borate and cuprous fluorophosphate and a hydrocarbon selected from the group consisting of olefins, aromatic hydrocarbons and mixtures of olefins and aromatic hydrocarbons, thereby forming a first extract phase and a first raffinate phase, separating said first extract and said first raffinate phase, and recovering from said extract phase a hydrocarbon fraction containing unsaturated aliphatic hydrocarbons in a substantially higher weight ratio to saturated aliphatic hydrocarbons than the original feed mixture and recovering from said raffinate phase a hydrocarbon fraction containing saturated aliphatic hydrocarbons in a substantially higher weight ratio to the unsaturated aliphatic hydrocarbons than in the original feed mixture.

While recovery of the unsaturated aliphatic hydrocarbons from the extract phase may be accomplished by the use of vacuum, heat or the like, usually it is preferred to displace such hydrocarbons from the extract by contacting said extract with unsaturated aliphatic hydrocarbons of a molecular weight different from those in the extract or, in the alternative, with vinyl aromatic hydrocarbons. The amount of such hydrocarbons used to displace unsaturated aliphatic hydrocarbons from the extract phase is at least a molar equivalent.

By means of the process disclosed herein, olefin and/or diolefin hydrocarbons may be separated from paraffin and/or naphthene hydrocarbons.

DESCRIPTION OF THE PREFERRED EMBODIMENTS

In order to further describe the present invention, particularly with respect to the preferred embodiments thereof, the following examples are presented.

EXAMPLE I

A first complex was prepared by dispersing 63.5 grams of powdered metallic copper along with 137.5 grams of $\text{CuF}_2 \cdot 2\text{H}_2\text{O}$ in 644 grams of toluene and then continuously introducing gaseous BF_3 into the dispersed medium until all solids had solubilized. The reaction mass was maintained at a temperature of approximately 110° C. and continuously agitated throughout addition of the BF_3 with continuous removal of the water generated. Agitation was continued for a period of several minutes and the product cooled back to ambient temperatures (73–75° F.). This first complex was intimately contacted with a mixture of 80.5 grams of n-dodecane and 14.5 grams of n-dodecene. Temperatures during the contacting period were ambient temperatures. An extract and raffinate phase rapidly formed and/or separated. The following table presents the weight percent concentration of n-dodecane and n-dodecene in the extract and raffinate phases, the concentration being calculated on a toluene- CuBF_3 free basis:

Component	Raffinate	Extract
n-Dodecane-----	95.2	10.1
n-Dodecene-----	4.8	89.9

EXAMPLE II

A first complex prepared as described in Example I was contacted with a mixture of 2.54 grams (39.1% by weight) of hexene-1 and 3.94 grams (60.9% by weight) of n-heptane. The amount of first complex employed was approximately 8.6 grams. An extract and raffinate phase rapidly formed and were separated. On analysis, the mixture of hexene-1 and n-heptane in the extract phase, normalized to 100%, was found to have a composition 67.8% by weight hexene-1 and 32.1% by weight n-heptane. The raffinate phase had a composition 85.9 weight percent n-heptane and 14.1 weight percent hexene-1. The raffinate phase contained 66.5 weight

percent of the toluene initially present in the first complex, the remainder being retained in the extract phase.

The extract obtained above was re-extracted with a non-complexing hydrocarbon diluent or solvent, in this case n-pentane. With 8.3 grams of the extract, 4.7 grams of n-pentane was intimately contacted. A new raffinate and extract phase formed and were separated. The new or re-extracted extract phase was found to consist of 52.4% by weight CuBF_4 , 12.7% by weight toluene, 0.8% by weight n-heptane, 27.8% by weight hexene-1 and 6.3% by weight n-pentane. The new raffinate phase consisted of 24.0% by weight toluene, 13.5% by weight n-heptane, 4.4% by weight hexene-1 and 58.1% by weight n-pentane. The weight percent hexene-1 and n-heptane in the re-extracted extract, calculated on a toluene, n-pentane and CuBF_4 free basis, is 97.2% by weight hexene-1 and 2.8% by weight heptane or an increase in hexene-1 percent concentration of 148.6% over the initial concentration in the feed.

EXAMPLE III

To demonstrate the recovery of olefins from the extract phase with an olefin hydrocarbon of a different molecular weight, the hexene-1 containing re-extracted extract of Example II was intimately contacted with pentene-1 at a temperature of 25° C. The amount of pentene-1 used was in a weight ratio of 2:1 to hexene-1 in the extract phase. An extract and a raffinate phase formed and were separated. The extract phase again contacted with pentene-1 in a weight ratio of 2:1. Again, an extract and raffinate phase formed and were separated. The analysis of percent by weight of the two raffinate phases and the final extract phase are presented in the following table:

Component	First raffinate	Second raffinate	Extract
Pentene-1-----	43.7	64.1	30.20
Hexene-1-----	31.6	23.0	8.70
Heptane-----	1.5	-----	-----
Toluene-----	23.2	12.9	2.70
CuBF_4 -----	-----	-----	58.60

The 8.7% by weight hexene-1 in the extract represented 27.4% by weight of the hexene initially present in the re-extracted extract contacted with the pentene-1. The mixture of hexene-1 and n-heptane contained in the first raffinate phase normalized to 100%, consisted of 95.5% by weight hexene-1 and only 4.5% by weight n-heptane and a second raffinate contained no n-heptane.

EXAMPLE IV

A first complex prepared as described in Example I was contacted with a 50-50 mixture of hexene-1 and cyclohexane. The temperature during the contacting period was approximately 25%. An extract and raffinate phase rapidly formed and were separated. The following table presents the weight percent concentration of hexene-1 and cyclohexane in the extract and raffinate phases, the concentration being calculated on a toluene- CuBF_4 free basis:

Component	Raffinate	Extract
Hexene-1-----	32.5	67.7
Cyclohexane-----	67.5	32.3

EXAMPLE V

A cuprous fluorophosphate first complex is prepared by dispersing 137.5 grams of $\text{CuF}_2 \cdot 2\text{H}_2\text{O}$ and 63.5 grams of powdered metallic copper and 644 grams of toluene and continuously introducing phosphorus pentafluoride until all solids are solubilized. The reaction mass is continuously agitated throughout the preparation of the first complex and maintained at a temperature within the range of 80 to 110° C. After all solids are solubilized, approximately 480 grams of sulfolane is added thereby forming two phases which are then separated. The extract phase represents the first complex.

To the cuprous fluorophosphate containing first complex prepared above, a 1:1 by weight mixture of cyclopentene and cyclopentane is contacted at a temperature of approximately 25° C. and at autogenous pressure. The weight ratio of cuprous fluorophosphate in the first complex to cyclopentene in the hydrocarbon mixture is approximately 1.5:1. Extract and raffinate phases form and are separated. The raffinate phase is found to contain a substantially higher ratio of cyclopentane to cyclopentene than was present in the original feed mixture. The extract phase is found to contain a substantially higher ratio of cyclopentene to cyclopentane than in the original feed mixture.

EXAMPLE VI

- 15 To demonstrate operation of the process of the present invention as a continuously operating process, a hydrocarbon mixture consisting of 70 percent by weight n-hexane and 30 percent cis-hexene-2 is continuously separated in an extraction column having approximately 20 perforated trays, each tray capable of operating at approximately 50 percent theoretical tray efficiency. A first complex is continuously introduced onto the top of the 20th tray from the bottom of the extraction column. This first complex is one prepared as follows: powdered metallic copper and $\text{CuF}_2 \cdot 2\text{H}_2\text{O}$ are dispersed in toluene, the weight ratio of Cu to $\text{CuF}_2 \cdot 2\text{H}_2\text{O}$ to toluene being 1:2.2 to 1:1.9. Gaseous BF_3 is then passed through the mixture until it is completely in liquid phase. The reaction mass is maintained at a temperature of approximately 110° C. and continuously agitated throughout addition of the BF_3 with continuous removal of the water generated. The agitation is continued for several minutes beyond the period of BF_3 addition and the product cooled to ambient temperatures (73-75° F.).
- 20 Concurrently with introduction of the first complex onto the top of the extraction column, the above-defined hydrocarbon feed mixture is continuously introduced into the column between the 10th and 11th tray and n-heptane is continuously introduced below the first tray.
- 25 The column is operated at a temperature within the range of 70 to 80° F. and at autogenous pressure. The weight ratio of first complex to feed mixture to n-heptane is 1:1.3:0.5. A raffinate, termed the first raffinate is continuously taken overhead from the extraction column and an extract, termed the first extract is continuously taken from the bottom. The raffinate contains n-hexane and cis-hexene-2 in a weight ratio of 69:1. The extract contains n-hexane and cis-hexene-2 in a weight ratio of 1:30 and contains approximately 1.4 percent of the n-hexane present in the original mixture and about 97 percent by weight of the cis-hexene-2 present in such original mixture.
- 30 The extract from the extraction column is continuously introduced into a second extraction column adjacent a top plate thereof. Heptene-2 is continuously introduced into the second extraction column adjacent the bottom thereof, the weight ratio of the extract from the first extraction column to the heptene-2 being 1:1. This second extraction column is operated at substantially the same temperatures and pressures as the first column. A raffinate, termed the second raffinate, is continuously taken overhead from the second extraction column and an extract, termed the second extract is continuously taken from the bottom. The second raffinate contains n-hexane and cis-hexene-2 in a weight ratio of 1:28. The extract has the composition of 33.9 percent by weight CuBF_4 , 20.8 percent by weight toluene, 0.9 percent by weight cis-hexene-2 and 44.4 percent by weight heptene-2. The extract from the second extraction column is recycled back to the first extraction column as a part of the first complex introduced therein.
- 35 The cuprous salts employed in forming the complexes used in carrying out the process of the present invention are cuprous tetrafluoroborate and cuprous hexafluorophosphate. Generally, these are referred to as cuprous
- 40
- 45
- 50
- 55
- 60
- 65
- 70
- 75

fluoroborate and cuprous fluorophosphate. Both of these salts are relatively unstable and cannot be readily formed as the salt. As a result, the usual practice is to form the salt in the presence of an organic compound with which the salt will complex, thereby forming the salt and the complex of the salt with the organic compound almost concurrently. This complex is referred to herein as the first complex.

The organic compounds in which the cuprous salts may be formed and with which such salts are immediately complexed to form the first complex may include any of a rather large number of such compounds. As will hereinafter be more fully discussed, the choice of organic compound is often dictated by the particular hydrocarbons in the hydrocarbon mixture to be separated. Generally, however, the organic compounds will be aromatic hydrocarbons. Such aromatic hydrocarbons may contain a single aromatic ring or may contain two or more condensed aromatic rings. In addition, the aromatic hydrocarbons may have substituents to the ring or may be condensed with one or more other ring structures which are paraffinic or olefinic in nature. Non-limiting examples of aromatic hydrocarbons suitable for use in preparing the cuprous salt-containing first complexes of the present invention are benzene, toluene, the xylene, various other polymethylbenzenes, such as mesitylene, isodurene, tri-, penta- and hexamethylbenzenes, ethylbenzene and the various polyethylbenzenes, isopropylbenzene, propylbenzene and the various polyisopropyl and polypropylbenzenes, the various butyl and pentylbenzenes and the like; substituted benzenes containing two or more different substituents such as ethyltoluene, isopropyltoluene, and ethylxylenes; naphthalene, the various methylnaphthalenes, and polymethylnaphthalenes, ethynaphthalene and the various polyethylnaphthalenes, the naphthalenes containing propyl, isopropyl, butyl, and pentyl substituents; the substituted naphthalenes containing two or more different substituents such as methylethynaphthalene, methylpropynaphthalenes, etc.; the various indanes such as methylindanes, ethylindanes, isopropyliindanes, etc.; the dihydronaphthalenes such as methyl, ethyl, propyl, and butyl substituted dihydronaphthalenes; the tetrahydronaphthalenes such as methyl, ethyl, propyl, and pentyl substituted tetrahydronaphthalenes and the like. In the preferred practice of the present invention, the aromatic hydrocarbons most often employed as the organic compound in forming the complexes of the present invention are benzene, naphthalene, partially hydrogenated naphthalenes, and the various alkylbenzenes and alkynaphthalenes having alkyl substituents of not more than four carbon atoms per substituent. Within this group of preferred aromatic hydrocarbons are such compounds as benzene, ethylbenzene, toluene, the xylenes, naphthalene and the methylnaphthalenes, dihydronaphthalene, and tetrahydronaphthalene and the like. A particularly useful group of aromatic hydrocarbons for use in forming the first complexes of the present invention is that including such compounds as toluene, ethylbenzene, ethyltoluene, xylenes and tetrahydronaphthalene.

The method of preparing the cuprous fluoroborate-aromatic hydrocarbon complexes which are used for the separation of hydrocarbon mixtures in accordance with the present invention may be any of those methods conventionally used. In U.S. Pat. 2,953,589, the preparation of cuprous fluoroborate-aromatic hydrocarbon complexes by the introduction of powdered copper, BF_3 and anhydrous HF into benzene or other aromatic hydrocarbons is disclosed. This method may be used for the purposes of the present invention. In addition, the cuprous fluoroborate-aromatic hydrocarbon complex may be prepared by dispersing $\text{CuF}_2 \cdot 2\text{H}_2\text{O}$ and metallic copper in an aromatic hydrocarbon and heating the reaction mixture while introducing gaseous BF_3 into the dispersed medium. This method is described in Journal of the American Chemical Society, vol. 74, p. 3702, 1952. This

latter described method is preferred for the practice of the present invention. In addition to these two methods of preparing the cuprous fluoroborate-aromatic hydrocarbon complex, any other of the methods known to those skilled in the art may be used.

Preparation of the cuprous fluorophosphate-aromatic hydrocarbon complex may be by any of those means known to those skilled in the art. Preferably, however, this complex is prepared in introducing anhydrous CuF_2 , metallic copper and phosphorous pentafluoride into an aromatic hydrocarbon medium and heating with agitation to an elevated temperature in excess of 75° C. The cuprous fluorophosphate-aromatic hydrocarbon complexes may on occasion be solid at room temperature and therefore, must be maintained at elevated temperatures for use in the process of the present invention or, in the alternative, be used along with a suitable solvent. It is believed that impurities in the system cause these solid complexes. In addition to the above method of preparing the cuprous fluorophosphate-aromatic hydrocarbon complex, any other method known to the art may be used.

As mentioned above, as an alternative to elevated temperatures, it is possible to use a solvent in the preparation of the cuprous fluorophosphate containing first complex to prevent formation of solid complexes. Such solvents include a wide range of organic compounds, particularly those compounds containing oxygen and/or sulfur. Ethers, ketones, sulfones, disulfides, thioethers, thioureas, nitro alkyls and aryls, trihydrocarbonyl phosphines, and the like, represent classes of useful solvent. While the particular solvent selected is primarily a matter of individual choice, it is somewhat preferred that the solvent be one selected from the group consisting of the alkyl and aryl sulfones, particularly such compounds as sulfolane and the alkyl sulfolanes.

In preparing the cuprous salt-organic compound first complexes for use in the separations processes disclosed herein, some care should be exercised in the selection of the organic compound to avoid use of an organic compound which itself may be difficultly separable from hydrocarbons of the mixture to be separated. Each mole of the cuprous salt-organic compound first complexes formed in accordance with the present invention generally will contain at least two moles of organic compound and one mole of the cuprous salt. Separation of hydrocarbon mixtures in accordance with the process disclosed herein, involves the displacement of one or more of the moles of organic compound from the first complex and substitution therein of unsaturated aliphatic hydrocarbon components of the mixture to be separated. Since the molecule of organic compound displaced by these unsaturated components generally mix freely with the components of the feed mixture which do not complex with the cuprous salt, the organic compound of the first complex should be one which may be readily and simply separated from the con-complexed hydrocarbons of the hydrocarbon mixture.

The amount of first complex employed in carrying out the separation of unsaturated aliphatic hydrocarbons from saturated aliphatic hydrocarbons in accordance with the process of the present invention may vary considerably. However, the amount most often used is such as to provide a mole ratio of the cuprous salt (CuBF_4 or CuPF_6) to the unsaturated aliphatic hydrocarbons in the mixture to be separated within the range of 0.25:1 to 2:1. Preferably, the amount will be such as to provide a mole ratio of cuprous salt to available unsaturated aliphatic hydrocarbons of 0.5:1 to 1:1.

It has been found particularly useful in carrying out the separations process of the present invention to use a con-complexible hydrocarbon diluent or solvent to aid in the formation of extract and raffinate phases and/or for further extraction of the extract phases to remove from such phases hydrocarbons which are not complexed with the cuprous salt. The use of such non-complexible hydro-

carbons as to further extract an extract phase is exemplified in the Example II above. In most instances, the non-complexible hydrocarbon employed is an aliphatic hydrocarbon of 3 to 15 carbon atoms. Non-limiting examples of such hydrocarbons are propane, n-butane, n-pentane, n-hexane, n-heptane, n-octane, n-nonane, n-decane, n-undecane, n-dodecane, n-tridecane, isobutane, isopentanes, isoheptanes, isodecanes, isododecanes, isotridecane, cyclopentane, cyclohexane, methylcyclohexane, cycloheptane, and the like. Most often, the saturated aliphatic hydrocarbons are paraffinic hydrocarbons and may be straight-chain or branched-chain. The most useful saturated aliphatic hydrocarbons are the paraffinic hydrocarbons of 4 to 7 carbon atoms per molecule. In selecting the particular non-complexible hydrocarbon diluent or solvent to use as above described, care should be exercised to avoid selecting one which itself will be difficultly separable from components of the resulting raffinate and extract phases.

In the event a non-complexible hydrocarbon is employed to aid in the formation of extract and raffinate phases and/or for further extraction of the extract phases, the amount used may vary widely. The actual amount of such hydrocarbons used will depend to a large extent on the amount of hydrocarbons in the hydrocarbon mixture to be separated which will not complex with the cuprous salt and on the degree of separation desired. Usually, however, about 0.5 to 10 volumes of the non-complexible hydrocarbon is used per volume of saturated aliphatic hydrocarbon in the feed mixture which is to be separated.

The separations process of the present invention may be practiced over a wide range of temperatures and pressures. Most often, however, the process is practiced at temperatures within the range of 0.195° C., preferably within the range of 25 to 150° C. The pressures employed for practicing the process of the present invention do not appear to be critical and may range from subatmospheric pressures to superatmospheric pressures. As a practical matter, it is usually desirable to operate at or near atmospheric pressure, the pressures ranging from as low as 50 mm. Hg to as high as 250 p.s.i.g. and higher.

In accordance with the process of the present invention, unsaturated aliphatic hydrocarbons are separated from saturated aliphatic hydrocarbons. Such separations include the separation of olefin hydrocarbons from paraffin and/or naphthene hydrocarbons and the separation of diolefin hydrocarbons from paraffin and/or naphthene hydrocarbons. The molecular weight range of hydrocarbons which may be separated include close boiling and difficultly separable hydrocarbons of from 2 to 25 carbon atoms and higher. Generally speaking, any mixture of unsaturated and saturated aliphatic hydrocarbons which is liquid or liquefiable under the conditions of separation may be successfully separated in accordance with the present invention. Liquefiable hydrocarbons include those which may be liquefied at the elevated temperatures suitable for operating the separations process of the present invention or which are liquefiable by mutual solubility with other components of the system or by solvents inert to the separations process. Such separations as the separation of pentene from pentanes, hexenes from hexanes, propylene from propane, pentenes from cyclopentane, hexenes from cyclohexane or methylcyclopentanes, dodecane from dodecene, and the like, may be carried out through the present separations process. In the preferred embodiment of the separations process of the present invention, olefin hydrocarbons containing 2 to 20 carbon atoms are separated from difficultly separable paraffin and/or naphthene hydrocarbons.

While the unsaturated aliphatic hydrocarbons contained in the extract phase may be recovered therefrom by any means such as heat, reduced pressure, and the like, it is usually preferred to displace these hydrocar-

bons from the extract phase by means of another hydrocarbon. Such other hydrocarbons useful in displacing the unsaturated aliphatic hydrocarbons are vinyl aromatic hydrocarbons and other olefin hydrocarbons, generally of a molecular weight different from the olefin hydrocarbons in the extract phase. Such vinyl aromatic hydrocarbons as styrene, alphamethylstyrene, vinyl toluene and the like are useful. The olefin hydrocarbons useful include those having as high as 20 carbon atoms and higher, again generally being those that are liquid or liquefiable at slightly elevated temperatures or by the use of solvents inert to the system or by mutual solubility with the components of the extract phase. Usually, the olefin hydrocarbons employed are those having less than 15 carbon atoms. In choosing the vinyl aromatic hydrocarbon or olefin hydrocarbon, care should be used that the hydrocarbon selected is not one which will itself be difficultly separable from other hydrocarbon components of the system.

What is claimed is:

1. A process for the separation of unsaturated aliphatic hydrocarbons from admixture with saturated hydrocarbons, said process comprising contacting a mixture of saturated and unsaturated aliphatic hydrocarbons with a first complex which comprises a complex of a cuprous salt selected from the group consisting of cuprous fluoroborate and cuprous fluorophosphate and a hydrocarbon selected from the group consisting of aromatic hydrocarbons, olefin hydrocarbons of a molecular weight different from those of the unsaturated aliphatic hydrocarbons within said mixture, and combinations of such aromatic hydrocarbons and olefin hydrocarbons, thereby forming an extract phase and a raffinate phase, separating said extract and raffinate phases, recovering from said extract phase a hydrocarbon fraction containing unsaturated aliphatic hydrocarbons in a substantially higher weight ratio to saturated hydrocarbons than in the original mixture, and recovering from said raffinate phase a hydrocarbon fraction containing saturated hydrocarbons in a substantially higher weight ratio to the unsaturated aliphatic hydrocarbons than in said original mixture.

2. The process of claim 1 wherein the cuprous salt is cuprous fluoroborate.

3. The process of claim 2 wherein the first complex comprises cuprous fluoroborate and an aromatic hydrocarbon.

4. The process of claim 3 wherein the aromatic hydrocarbon is selected from the group consisting of benzene, naphthalene, partially hydrogenated naphthalenes, the alkyl substituted derivatives of these wherein the alkyl substituents have no more than 4 carbon atoms per substituent, and mixtures of these.

5. The process of claim 4 wherein the aromatic hydrocarbon is toluene.

55. The process of claim 1 wherein said mixture is contacted with said first complex at a temperature within the range of 0 to 195° C.

60. The process of claim 1 wherein said unsaturated aliphatic hydrocarbons are olefin hydrocarbons and wherein said saturated hydrocarbons are of the group consisting of paraffin hydrocarbons, naphthene hydrocarbons and mixtures thereof.

65. The process of claim 7 wherein said saturated and unsaturated aliphatic hydrocarbons are those having 2 to 20 carbon atoms per molecule.

9. The process of claim 1 wherein said unsaturated aliphatic hydrocarbons are recovered from said extract phase by contacting said extract phase with vinyl aromatic hydrocarbons, said vinyl aromatic hydrocarbons being in at least molar equivalent with the unsaturated aliphatic hydrocarbons within said extract phase.

10. The process of claim 1 wherein said unsaturated aliphatic hydrocarbons are recovered from said extract phase by contacting said extract phase with at least a molar equivalent of an olefin hydrocarbon of a molec-

ular weight different from that of the unsaturated aliphatic hydrocarbons in said extract phase.

11. The process of claim 1 wherein said first extract is re-extracted with a non-complexible hydrocarbon.

12. The process of claim 11 wherein said non-complexible hydrocarbon is a saturated hydrocarbon of 3 to 15 carbon atoms.

13. The process of claim 1 wherein said first complex is present in an amount such as to provide a mole ratio of cuprous salt to the unsaturated aliphatic hydrocarbons in said mixture of saturated and unsaturated aliphatic hydrocarbons within the range of 0.25:1 to 2:1.

14. The process of claim 1 wherein the unsaturated aliphatic hydrocarbons are olefin hydrocarbons of no greater than 20 carbon atoms per molecule.

15. The process of claim 1 wherein said first complex comprises cuprous fluoroborate, an aromatic hydrocarbon and an olefin hydrocarbon.

16. The process of claim 15 wherein the aromatic hydrocarbon is selected from the group consisting of benzene, naphthalene, partially hydrogenated naphthalenes, the alkyl substituted derivatives of these wherein the alkyl substituents have no more than 4 carbon atoms per substituent, and mixtures of these.

17. The process of claim 15 wherein the olefin hydrocarbon is one having 2 to 20 carbon atoms per molecule.

18. A process for the separation of unsaturated aliphatic hydrocarbons from saturated hydrocarbons comprising introducing a mixture of saturated and unsaturated hydrocarbons into a first extraction column intermediate the ends thereof, concurrently introducing adjacent to top of said extraction column a first complex comprising a cuprous salt selected from the group consisting of cuprous fluoroborate and cuprous fluorophosphate and a hydrocarbon selected from the group consisting of aromatic hydrocarbons, olefin hydrocarbons and mixtures of olefins and aromatic hydrocarbons, concurrently introducing into said extraction column adjacent the bottom thereof a non-complexible hydrocarbon, removing overhead from said first extraction column a first raffinate containing a hydrocarbon fraction substantially richer in the saturated hydrocarbons of said mixture than

the original hydrocarbon mixture, removing from the bottom of said extraction column a first extract phase, introducing said first extract phase into a second extraction column intermediate the ends thereof, concurrently introducing a hydrocarbon selected from the group consisting of olefin hydrocarbons of a molecular weight different from the unsaturated aliphatic hydrocarbons in said mixture and vinyl aromatic hydrocarbons, said hydrocarbon being introduced into a quantity which is at least in molar equivalent to the unsaturated aliphatic hydrocarbons in said first extract phase, concurrently introducing non-complexible hydrocarbons into said second extraction column, removing from the bottom of said second extraction column a second extract phase at least a portion of which is recycled to said first extraction column as at least a portion of said first complex, removing overhead from said second extraction column a second raffinate phase containing a hydrocarbon fraction substantially richer in the unsaturated aliphatic hydrocarbons of said mixture than said original hydrocarbon mixture.
